(57) **CLAIM**

The ornamental design for a vehicle awning, as shown and described.

DESCRIPTION

FIG. 1 is a top, front, perspective view of a first version of a vehicle awning showing the new design;

FIG. 2 is a bottom, rear, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a top, front, perspective view of a second version of a vehicle awning showing the new design;

FIG. 10 is a bottom, rear, perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and

FIG. 16 is a bottom view thereof.

FIG. 17 is a top, front, perspective view of a third version of a vehicle awning showing the new design;

FIG. 18 is a bottom, rear, perspective view thereof;

FIG. 19 is a front view thereof;

FIG. 20 is a rear view thereof;

FIG. 21 is a right side view thereof;

FIG. 22 is a left side view thereof;

FIG. 23 is a top view thereof; and,

FIG. 24 is a bottom view thereof.

The broken lines shown in FIGS. 1-16 represent portions of the vehicle awning that form no part of the claimed design. In FIGS. 1-8, the vehicle awning is shown with symbolic breaks. The appearance of any portion of the article between the break lines forms no part of the claimed design.

1 Claim, 24 Drawing Sheets
